UNITED STATES PATENT OFFICE

2,337,897

FLUID ACTUATED ROTARY TOOL

Francis A. Jimerson, Athens, Pa., assignor to Ingersoll-Rand Company, New York, N. Y., a corporation of New Jersey

Application December 3, 1941, Serial No. 421,444

2 Claims. (Cl. 121—34)

This invention relates to fluid actuated tools, and more particularly to a controlling device for a fluid actuated tool of the portable rotary type, as for example tapping machines, drills, reaming machines and the like.

One object of the invention is to enable the controlling device to be conveniently manipulated with a minimum of effort.

Another object is to enable the direction of rotation of the rotary parts of the tool to be controlled in a simplified and novel manner.

Other objects will be in part obvious and in part pointed out hereinafter.

In the drawing accompanying this specification and in which similar reference numerals refer to similar parts,

Figure 1 is a side elevation, partly broken away, of a fluid actuated rotary tool embodying the invention, and

Figures 2, 3 and 4 are transverse views taken through Figure 1 on the lines 2—2, 3—3 and 4—4, respectively.

Referring more particularly to the drawing, the tool, designated in general by 20, comprises a casing 21 having a laterally extending grip portion 22 near its rearward end and a chuck 23 at its opposite end.

In the portion of the casing 21 adjacent the grip 22 is a bore 24 having arranged therein a tubular member 25 that serves as a container for a cylinder 26 and front and rear end heads 27 and 28, respectively. At the rearward end of the tubular member 25 is an introverted flange 29 to serve as a seat for the head 28 and a nut 30 is threaded into the opposite end of the tubular member 25 and seats against the head 27 for clamping the heads 27 and 28 and the cylinder in fixed positions within the tubular member 25.

The said heads and cylinder may, if desired, be additionally secured with respect to each other and with respect to the tubular member by keys or pins (not shown).

The interior of the cylinder 26 serves as a chamber 31 and contains a rotor 32 having trunnions 33 at its ends that extend through the heads 27 and 28 into the inner races of anti-friction bearings 34 arranged within annular extensions 35 on the outer surfaces of the heads 27 and 28. The front trunnion 33 extending through the head 27 may be connected, in a well known manner, to transmission means (not shown) within the front part of the casing 21 for rotating the chuck 23. The foremost annular extension 35 preferably extends closely adjacent the end surface of a member 36 with-

in the casing to prevent endwise movement, in a forwardly direction, of the tubular member 25 and the parts arranged therein. These elements are, moreover, restrained against movement in a rearwardly direction by a shoulder 37 in the casing 21 that engages the rearward end of the tubular member 25.

The rotor 32 is actuated by pressure fluid conveyed to the chamber 31 through the grip member 22 which has a supply passage 38 extending therethrough and a bushing 39 threaded into the outer end of the supply passage for connection with a supply conduit (not shown). The portion 40 of the supply passage adjacent the bushing 39 is somewhat enlarged, and at its inner end is a beveled seat 41 for a poppet valve 42 that controls the flow of pressure fluid through the supply passage. The valve 42 has a stem 43 extending upwardly through the grip member into a recess 44 in the forward side of the grip member.

The valve is normally held upon the seat 41 by a spring 45 interposed between the valve and the bushing 39, and in the recess 44 is a rocker 46 that is pivotally mounted upon a pin 47 and has a laterally extending arm 48 intermediate its ends to engage the end of the stem 43. The upper end of the rocker 46 extends into the path of a pin 49 carried by a plunger 50 slidable transversely of the grip member 22 for imparting movement to the rocker 46 to unseat the valve 42.

The rotor 32 is intended for reverse operation and pressure fluid for actuating it is introduced selectively into the chamber 31 on opposite sides of and adjacent the point of minimum clearance between the rotor and the wall of the chamber 31 through inlet passages 51 and 52 in the cylinder 26 and the tubular member 25. Preferably the outlet ends of the inlet passages open into enlarged cavities 53 of suitable proportions in the wall of the cylinder 26 to assure the delivery of an ample supply of pressure fluid to the cells 54 between the protruding ends of the vanes 55 slidable radially in the rotor 32.

In the sides of the cylinder 26 and the tubular member 25 opposite to the point of minimum clearance between the rotor and the cylinder are exhaust ports 56 through which exhaust fluid may pass from the chamber 31 into an exhaust chamber 57 in the casing 21, and in the wall of the casing 21 are exhaust ports 58 through which exhaust fluid may pass from the chamber 57 to the atmosphere.

The chamber 57 encircles the tubular member

25 and in the lower part thereof is a boss 59 that defines the outlet opening of the supply passage 38 and has a curved surface 60 to conform with the curvature of the periphery of the tubular member for which it may act as a bearing. In the boss 59 and in concentric relationship with the supply passage 38 is a recess 61 for the accommodation of a packing member 62 that bears against the periphery of the tubular member 25 to prevent the leakage of pressure fluid from the supply passage 38 into the exhaust chamber 57. The packing member 62 is hollow having an opening 63 therethrough to afford communication between the supply passage 38 and the inlet passages 51 and 52.

In the form of the invention illustrated, the direction of rotation of the rotor 32 is controlled by rotating the tubular member 25 to bring one or the other of the inlet passages 51 and 52 into communication with the supply passage 38. To this end an actuator, in the form of a plate 64, is arranged between the rearmost annular extension 35 and the end wall 65 of the casing 21, and on the plate 64 are forwardly extending fingers 66 that lie in slots 67 in the introverted flange 29 to effect interlocking engagement between the plate 64 and the tubular member 25.

On the opposite side of the plate 64 is a stem 68 that projects through the end wall 65 and carries a knob 69 whereby rotational movement may be manually imparted to the tubular member 25. The knob is secured fixedly to the stem 68 by a pin 70 extending through the two parts and has a recess 71 for the accommodation of a locking member 72, shown as being in the form of a ball, for engagement with a depression, or depressions, 73 in the adjacent surface of the end wall 65. A spring 74 in the bottom of the recess 71 constantly maintains the ball 72 in position for engagement with the depressions 73.

The limiting positions rotatively of the tubular member 25 with respect to the casing 21 are determined by a stop device consisting of a pin 75 in the knob 69 and extending into an arcuate slot 76 in the outer surface of the end wall 65, the slot 76 being of such length that when the pin 75 is moved into engagement with an end of the slot 76 an inlet passage, either 51 or 52 depending upon the direction of rotation of the knob 69, will be in full registry with the supply passage 38.

Preferably the grip member 22 is provided with a reservoir 77 for oil that may be introduced into the pressure fluid flowing to the rotor through an orifice 78 leading from the reservoir to the portion of the supply passage 38 lying between the valve seat 41 and the bore 24.

In the operation of the device, and assuming the cylinder assembly to occupy a position in which the inlet passage 51 registers with the supply passage 38, as illustrated in Figures 1 and 2 of the drawing, the plunger 50 is actuated to unseat the valve 42. Pressure fluid then flows through the supply passage 38 and the inlet passage 51 into the chamber 31 for driving the rotor in a clockwise direction as Figure 1 is viewed from the right hand end. The pressure fluid performing this work is exhausted from the chamber 31 through the ports 56 into the chamber 57, thence through the exhaust ports 58 to the atmosphere. Such air as may be present in the cells 54 after the vanes 55 have passed the exhaust ports 56 will be carried to the inlet passage 52 and pass therethrough into the exhaust chamber 57.

In the event that it be intended to effect reverse operation of the rotor, the tubular member 25 is rotated by means of the knob 69 to bring the inlet passage 52 into communication with the supply passage 38 and to place the inlet passage 51 into position to communicate with the exhaust chamber 57. The pressure fluid then flowing into the chamber 31 will cause the rotor 32 to rotate in a counterclockwise direction and will exhaust through the exhaust ports 56, the exhaust chamber 57 and the exhaust ports 58 to the atmosphere, and, of course, any air remaining in the cells 54 after the vanes have passed the exhaust ports 56 will flow into the exhaust chamber 57 through the inlet passage 51.

I claim:

1. A fluid actuated rotary tool, comprising a casing having a supply passage and an atmospheric exhaust passage, a tubular member rotatable in the casing, a cylinder in the tubular member having a chamber, a pair of radially spaced inlet passages in the tubular member and the cylinder opening into the chamber, there being a free exhaust port in the cylinder and the tubular member to communicate the chamber with the exhaust passage, heads in the tubular member for the chamber, means for securing the cylinder and the heads to the tubular member, a rotor arranged eccentrically in the chamber and the point of minimum clearance between the rotor and the cylinder being diametrically opposite the exhaust port, and means for rotating the cylinder to different positions within the casing to selectively bring either inlet passage into communication with the supply passage for causing the rotor to turn in one direction or the other and to simultaneously bring the other inlet passage into communication with the exhaust passage to afford an additional outlet for the escape of fluid from the chamber.

2. A fluid actuated rotary tool, comprising a casing having a bore and an exhaust chamber intermediate the ends of the bore, a free atmospheric exhaust port in the casing for the exhaust chamber, a supply passage in the casing opening into the bore in the transverse plane of the exhaust chamber, a tubular member rotatable in the bore extending through the exhaust chamber, a cylinder in the tubular member having a rotor chamber, a free exhaust port in the cylinder and the tubular member to afford communication between the rotor chamber and the exhaust chamber, heads in the tubular member for the rotor chamber, means for securing the cylinder and the heads to the tubular member, a rotor arranged eccentrically within the rotor chamber and the point of minimum clearance between the rotor and the cylinder being diametrically opposite the exhaust port, and vanes slidable in the rotor cooperating with the rotor and the wall of the rotor chamber to define cells within the rotor chamber, there being inlet passages in the cylinder and the tubular member for the rotor chamber on the opposite sides of the point of minimum clearance between the rotor and the cylinder, and means for rotating the cylinder to different positions within the casing to selectively bring either inlet passage into registry with the supply passage for causing the rotor to turn in one direction or the other and to simultaneously bring the other inlet passage into communication with the exhaust passage to vent the cells after the said cells have passed across the exhaust port for the rotor chamber.
